UNITED STATES PATENT OFFICE.

MANLOVE BUTLER, OF VERNON, ASSIGNOR TO PLEASANT C. MCGANNON,
OF NORTH VERNON, INDIANA.

HAY-RAKE.

SPECIFICATION forming part of Letters Patent No. 252,586, dated January 17, 1882.

Application filed November 26, 1881. (Model.)

To all whom it may concern:

Be it known that I, MANLOVE BUTLER, a citizen of the United States, resident of Vernon, in the county of Jennings and State of Indiana, have invented a new and valuable improvement in Hay-Rakes; and I do hereby declare that the following is a full, clear, and exact description of the construction and operation of the same, reference being had to the annexed drawings, making a part of this specification, and to the letters and figures of reference marked thereon.

Figure 1 of the drawings is a representation of a sectional view, partly in elevation. Fig. 15 2 is a similar view, showing the lever sprung; and Fig. 3 is a perspective view.

This invention has relation to hay-rakes; and it consists in the construction and novel arrangement of the slide-joint sections of the holding or controlling lever or clamp, the brace-section pivoted to the handle-section, and the automatic catch therewith connected, all as hereinafter set forth, and especially pointed out in the claims appended.

25 In the accompanying drawings, the letter A designates the revolving rake-head, which is held in steady position for gathering the hay by means of clamp-lever B, having a clamping-band, C, which passes around a journal band 30 or ring, D, having marginal flanges a to keep the clamping-band in proper position at all times, whether loose or fast.

35 E designates the lateral draft-bars, to which the journals b at the ends of the center bar of the rake-head are pivoted.

The clamp-lever B consists of three parts or sections, to wit: the bearing or clamp section F, the handle section G, and the brace-section H, these parts being connected together in the 40 following manner to form a single lever: The end section, F, is formed with a concave bearing or seat, c, at its end, in which is received the journal D of the rake-head. It is also provided with a clamping-band, C, which extends 45 around the journal D, and is adjustably fastened to the brace-section H by means of clamp-screws e passing through slots g of the band. The upper portion of the clamp-section is recessed from the shoulder h to provide a seat, k,

for the brace-section. The end of the clamp-section is provided with lateral stud-projections l.

The handle G is provided with lateral or cheek plates m, which extend on each side of the clamp-section, as indicated at n, and are slotted longitudinally at s to engage the projections l of said clamp-section. The extended ends n of these cheek-plates project above the clamp-section to receive between them a portion of the brace-section, to which they are pivoted, as indicated at p. To one of the cheek-plates is pivoted an angular gravity or spring catch, K, the stem f of which is extended upward along the handle G, so that it can be easily reached by the operator when required. Between the cheek-plates a recess or seat, r, is formed to receive the upper end of the brace-section H, the lower end of which is cut obliquely and abuts against the shoulder h of the clamp-section, said shoulder being provided with a pin-guide, t, which engages a perforation 70 in the end of the brace and keeps it in position. The upper end of the brace-section, which extends across the slide-joint connection of the handle and clamp sections and is received in the recess r of the handle, is provided with a 75 catch projection or stud, v, with which the lever-catch K is designed to engage when the brace-section is seated in the recesses of the other two sections, and is in close contact with said sections, forming a rigid lever and holding 80 the journal of the rake-head firmly in the clamp-seat at its end. When the catch K is disengaged by raising its stem the liberated end of the brace H flies up and the entire lever bends upward at the slide-joint. This movement loosens the band-connection on the journal D and allows the rake-head to turn over easily and deposit its load without jarring or inconvenience to the operator. Then by raising the handle quickly the brace is brought 85 into its bearings, drawing the band-clamp tight on the journal of the rake-head, the catch K automatically securing the parts together. The inner corner, x', of the oblique end x of the brace-section is always in contact with the 90 shoulder h of the clamp-section, and forms a fulcrum, on which the brace vibrates. When the brace is down the upper corner, x', of the

oblique end is drawn away from the shoulder, and in this manner the clamp-band is tightened on the journal; but when the brace is liberated its end approaches the shoulder 5 squarely, and the band is thereby rendered loose on the journal.

What I claim, and desire to secure by Letters Patent, is—

1. In a controlling-lever for hay-rakes, the combination, with the end sections and their slide-joint connection, of the brace-section and the automatic catch, substantially as specified.

2. In a controlling-lever for hay-rakes, the combination, with the shouldered clamp section F and its clamp-band C, of the handle G, 15 its slide joint cheek-plates m, the pivoted brace

section H, and the catch K, substantially as specified.

3. A controlling-lever for hay-rakes, having its handle and clamp sections connected by 20 slide-joint plates, to which a brace-section having an oblique end and carrying one end of the clamping-band is pivoted, substantially as specified.

In testimony that I claim the above I have 25 hereunto subscribed my name in the presence of two witnesses.

MANLOVE BUTLER.
